UNITED STATES PATENT OFFICE.

LEVI D. GIBSON, OF THURBER, TEXAS, ASSIGNOR OF TWO-THIRDS TO
ROBERT LOFLIN, OF THURBER, TEXAS, AND HERMAN F. SCHEER, OF
DALLAS, TEXAS.

MECHANICAL MOVEMENT.

SPECIFICATION forming part of Letters Patent No. 716,028, dated December 16, 1902.

Application filed March 22, 1902. Serial No. 99,471. (No model.)

To all whom it may concern:

Be it known that I, LEVI D. GIBSON, a citizen of the United States, residing at Thurber, in the county of Erath and State of Texas, 5 have invented a new and useful Mechanical Movement, of which the following is a specification.

This invention relates to mechanical movements, and is designed to provide improved 10 means for producing alternating rotary movements, and while this means may be employed for a variety of purposes it is particularly designed for imparting movement to the dasher-stems of churns and also to the rubber stems 15 of washing-machines.

Another object is to convert a continuous rotary movement into alternating rotary movement, so as to adapt the device for manual operation through the medium of a crank-20 handle and also to arrange the device so that it may be conveniently mounted upon the top 25 or lid of a churn or washing-machine.

With these and other objects in view the present invention consists in the combination 30 and arrangement of parts, as will be herein-after more fully described, shown in the accompanying drawings, and particularly pointed out in the appended claims, it being understood that changes in the form, proportion, size, and minor details may be made 35 within the scope of the claims without departing from the spirit or sacrificing any of the advantages of the invention.

In the drawings, Figure 1 is a perspective 40 view of an embodiment of the present invention particularly adapted for use in connection with washing-machines. Fig. 2 is a longitudinal sectional view thereof.

Like characters of reference designate corresponding parts in both figures of the drawings.

Referring to the accompanying drawings, 1 designates a base or support, which in one specific application of the invention may be 45 the lid or cover of a churn or washing-machine. Upon the top of this lid or support and at one side of the center thereof there is provided a bracket 2, which is fastened to the support in any suitable manner and preferably disposed substantially radially thereof.

At the outer end of the bracket rises a standard 3, and a corresponding standard 4 rises from the inner end of the bracket, this latter standard being provided with a longitudinal slot 5, which is disposed in the same plane 55 with the two standards. The top of the standard 3 is provided with a notch or seat 6 for the reception of the operating-shaft, and the upper end of the standard 4 is provided with a lateral extension 7, which is directed away 60 from the standard 3, and is provided in its upper face with a groove 8, the bottom of which lies in alignment with the bottom of the notch or seat 6.

Between the lateral extension 7 and the lid 65 or support is an upstanding rotatable head 9, which is provided with an upper pivot or trunnion 10, rotatably fitted in a socket or bearing 11, formed in the under side of the extension 7, and the lower end of the head is 70 provided with a trunnion or pivot 12, mounted in the opening 13, formed through the support. It will be understood that the lower journal 12 may be extended to form a dasher-stem, or it may be provided with means for 75 connection with a stem or other part to be rotated; but as this forms no part of the present invention it has not been shown in the drawings. Throughout the greater part of the length of the head 9 there is formed a spiral slot 14.

A substantially horizontal drive-shaft 15 is mounted in the bearing-seat 6 and also in the groove 8, within which it is held by means of suitable inverted-U-shaped straps or bearing-clips 16. At the outer end of this shaft there is provided a crank-handle 17, and the intermediate portion of the shaft is provided with a double crank 18, which works between the standards 3 and 4. 90

To transfer motion from the crank-shaft to the rotatable head 9 there is provided a connecting-rod or link 19, the upper end of which is provided with a hook or eye 20 to embrace the outer end of the double crank and form a 95 loose or pivotal connection therewith. The lower end of the connecting-rod or link is provided with a lateral arm 21, which works in the guide-slot 5 and also in the spiral slot 14 in the head 9, the outer end of the arm 21 100

being bent laterally, as indicated at 22, so as to lie transversely across the slot 14, and thereby provide a head or stop to prevent endwise displacement of the arm from the slot.

From the foregoing description it will be understood that power is applied to the crank-handle 17, so as to rotate the shaft 15, and thereby apply an endwise-reciprocatory movement to the link or connecting-rod 19. The upper end of the connecting-rod of course describes a circle with the crank 18; but its lower end works vertically in a substantially straight line as the arm 21 is confined within the guide-slot 5, and as the arm reciprocates vertically and works in the spiral groove 14 the head 9 will be rotated in one direction during the upward movement of the arm and in the opposite direction during the downward movement of the arm, whereby alternating rotary movements are imparted to the head 9 by a continuous rotary movement of the crank-handle and power-shaft.

It is apparent that the device of the present invention is extremely simple and is particularly adapted for mounting upon the lid or cover of a washing-machine or churn in such a manner as to be readily connected to the stem thereof for operating the dasher or rubber. Furthermore, all of the parts are readily accessible for repairs, whereby it may be maintained in effective working condition and also be conveniently set up in position for operation.

35 What I claim is—

1. The combination with a base, of a pair of standards rising therefrom, one of the standards having a longitudinal slot, a spirally-slotted rotatable member mounted upon the base and adjacent to the outer side of the slotted standard, a power-shaft mounted upon the standards and having a crank working between the same, a connecting-rod pivoted to the crank and provided with a lateral arm working in the slot of the standard and also in the spiral slot of the rotatable member, and a head carried by the arm and extending transversely across the slot of the rotatable member to prevent displacement thereof.
2. The combination with a base, of a pair of standards rising therefrom, one of the standards having a longitudinal slot and also provided at its upper end with an outwardly-

directed lateral extension, a rotatable spirally-slotted member having its upper end 55 journaled in the extension of the standard and its lower end journaled in an opening formed in the base, a power-shaft mounted upon the standards and provided with an intermediate crank working between the said standards, a crank-handle upon one end of the shaft, and a connecting-rod having one end pivoted to the crank and its opposite end provided with a lateral arm working in the slot of one of the standards and also in the 65 spiral slot of the rotatable member, the outer end of the arm having a head extending transversely across the spiral slot to prevent endwise displacement of the arm.

3. The combination with a lid or cover having a central opening, of a pair of standards rising from the lid at one side of the opening therein, the standard which is next to the opening being provided with a longitudinal slot, and a transverse extension at its upper 75 end overhanging the opening in the lid and provided in its under side with a bearing-socket aligned with said opening in the lid, an 80 upstanding spirally-slotted rotatable member having a reduced journal at its upper end 85 which is mounted in the socket in the extension of the slotted standard, the lower end of the rotatable member having a reduced journal projected through the opening in the lid with its lower extremity adapted for connection with a part to be driven, a power-shaft mounted upon the extension of the slotted standard and upon the top of the other standard, and provided with a crank working between the standards, an operating crank- 90 handle carried by the outer end of the shaft, a connecting-rod pivotally hung from the intermediate crank and provided at its lower end with a laterally-projected arm working in the guide-slot of the standard and also in 95 the spiral slot of the rotatable member, and a cross-head carried by the arm and extended across the spiral slot to prevent displacement of the arm therefrom.

In testimony that I claim the foregoing as 100 my own I have hereto affixed my signature in the presence of two witnesses.

LEVI D. GIBSON.
